WINDOW FRAME

Filed July 12, 1929

Inventor

Richard Salomon

By his Attorney

US Attorney
Marvin Hoffman

UNITED STATES PATENT OFFICE

RICHARD SALOMON, OF NEW YORK, N. Y.

WINDOW FRAME

Application filed July 12, 1929. Serial No. 377,696.

This invention relates to improvements in window frames, particularly metal window frames, and it is the principal object of my invention to provide said frames with sash operating and holding means replacing the customary sash weights and their cords.

Another object of my invention is the provision of a window frame allowing a ready mounting and removal of all the parts thereof and doing away with the disadvantages incident to the use of sash cords, guide rollers therefor and weights.

A further object of my invention is the provision of a metal window frame allowing a ready opening of the windows to any desired width and holding said windows in their adjusted positions and ensuring a tight fitting and guiding of the sashes to avoid rattling, and a making of the window closure tight by means of suitable rubber strips so as to prevent draft and the entrance of rain or snow, etc.

A still further object of my invention is the provision of a metal window frame equipped with rack teeth to be engaged by spring controlled hooks on the sashes, and allowing a ready removal of the windows for cleaning and other purposes.

These and other objects of my invention will become more fully apparent as the description thereof proceeds, and will then be specifically defined in the appended claims.

In the accompanying drawings forming a material part of this disclosure:

Fig. 1 is a perspective view of a window frame constructed according to my invention.

Fig. 2 is a fragmentary sectional front elevation of a window frame.

Fig. 3 is a cross-section on line 3—3 of Figure 2.

As illustrated, the metal window frame 10 is provided with the usual guide grooves 11 for the upper sash 12, and 13, for the lower sash 14 of windows 15 and 16 respectively.

The inner faces of guide strips 17 and 18 forming the guide groove 13 are equipped with rack teeth 19 and 20 respectively, the rack teeth for the upper sash extending somewhat beyond the upper end of the rack teeth for the lower sash.

The lower sash has formed therein near its lower end a chamber 21 in which an angular spring 22 is attached with its foot part 23 to the bottom of the chamber, while the upper end of the upright arm of the spring is formed into a hook 24 adapted to engage between the teeth of rack 19 and kept in this engagement by means of a curved spring 25 attached at its upper end to the inner rear wall of chamber 21, while its free end engages the rear face of spring 22 and normally presses the hook thereof into engagement with the rack teeth 19.

Spring 22 has formed therewith intermediate its ends a presser or push pin or stud 26 extending to the outside of the sash and carrying there a head 27.

The hook 24 projects through an opening 28 in the front plate 30 of chamber 21.

The upper sash 12 has also formed therein near its lower end a chamber 31 closed by a front plate 32 having an opening 33 formed therein through which a hook 34 extends into engagement with the rack teeth 20. This hook 34 is made integrally with a plate 35, 75 in approximately the middle thereof, and extending longitudinally to the front wall of chamber 31. From the ends of said plate 35 extend studs 36, 37, towards the outside of the sash and carry there heads 38, 39, respectively.

The inner ends of studs 36, 37, project somewhat beyond the inner face of the plate 35, and have wound about them and secured thereto the outer ends of springs 40 and 41, 85 the opposite ends of which are wound about and attached to pins 42, 43, projecting into chamber 31.

Suitable handles 44, 45 on the lower and upper sashes facilitate the operation of the sashes while suitable locking devices may be provided to lock both sashes against movement.

My metal window frame operates in practice as follows:

If it is desired to lift the lower sash, an inward pressure exerted on head 27 will disengage hook 24 from the rack teeth 19, so that the sash may now be lifted by means of handle 44 to any desired height, where-

upon upon release of head 27 the hook will engage again the rack teeth 19 under the action of spring 25, so that the sash will be securely held in any of its adjusted positions.

- 5 The upper sash movements are controlled in a similar manner by pressing heads 38 and 39 and their stems inwardly against the action of springs 40 and 41, so that hook 34 is disengaged from rack teeth 20, and the sash
10 may now be lowered to any desired extent, and be held in any of its adjusted positions by re-engagement of hook 34 with the rack teeth 20 under the action of springs 40, 41, after release of the pressure on heads 38, 39.
15 It will be understood that I have described and shown some of the possible practical constructions of my metal window frame and that I may make changes therein such as are warranted by the appended claim without departure from my invention.

Having thus described my invention what I claim as new, and desire to secure by Letters Patent is:

In a metal window, sash guides and sashes guided therein, rack teeth formed on part of said guides, chambers formed in the sashes, an angular bracket in one of said chambers, the chamber for the lower sash, the horizontal arm of said bracket attached to the bottom of said chamber the end of the vertical arm of said bracket formed into a hook engaging between the teeth of said guides, and a curved leaf spring attached at one end to the inner wall of said chamber oppositely disposed to said hook, its lower free end bearing against the hook arm of said bracket for pressing the same into engagement with said rack teeth, and a headed stud extending from said hook to the outside for allowing a repressing of the same into the chamber to disengage it from the rack teeth, a front plate for the other of said chambers in the upper sash having an opening therein, a plate bearing against said front plate, a hook formed with said plate extending through the opening of said front plate into engagement with the rack teeth, studs extending from the ends of said hook plate towards the outside and carrying heads, and springs wound at one end about the inner ends of said studs, and pins projecting into said chamber about which the other ends of said springs are wound to normally press said hook into engagement with said rack.

In witness whereof I have signed my name to this specification.

RICHARD SALOMON.
